Calf Raise Platform by Achilles dated no date given. Found online [Aug. 27, 2020] <https://achilles3dx.com/calf-raise-platform/>.*

Primary Examiner — Ryan Harvey

(74) Attorney, Agent, or Firm — QuickPatents; Kevin Prince

(57) **CLAIM**

The ornamental design for a calf-raise platform, as shown and described.

DESCRIPTION

FIG. 1 is a perspective view of a calf-raise platform, showing my new design;

FIG. 2 is a top perspective view thereof;

FIG. 3 is a bottom perspective view thereof;

FIG. 4 is a front elevational view thereof, the rear elevational view being a mirror image thereof;

FIG. 5 is a left-side elevational view thereof, the right-side elevational view being a mirror image thereof;

FIG. 6 is a top plan view thereof; and,

FIG. 7 is a bottom plan view thereof.

The broken lines showing a person and an exercise machine in FIG. 1 depict environmental matter and form no part of the claimed design.

1 Claim, 4 Drawing Sheets
